UNITED STATES PATENT OFFICE.

BENJAMIN GOLD, OF HOBART, INDIANA.

HANGER UNIT.

1,316,298.

Specification of Letters Patent. Patented Sept. 16, 1919.

Application filed June 9, 1919. Serial No. 302,782.

To all whom it may concern:

Be it known that I, BENJAMIN GOLD, a citizen of the United States, residing at Hobart, in the county of Lake and State of Indiana, have invented a new and useful Improvement in Hanger Units, of which the following is a specification.

My invention relates to hanger units for use in repairing the roofs of furnaces, as 10 for example open-hearth furnaces, it having been devised for use, more particularly, though not exclusively, in carrying out my improved method forming the subject of my pending application for U. S. Patent, 15 Serial No. 289,338, filed April 11, 1919.

As a preface to the following description of my improved device, and as explanatory of the general conditions which give rise to its use, it may be said that the heat to which 20 the roofs, especially open-hearth furnace roofs, are subjected, sooner or later burns out portions of the roof structure, requiring the repairing thereof. Sometimes the burned out portion extends entirely through 25 the upper surface of the roof, and sometimes short thereof, and in the repairing operation the impaired portion of the roof is cut out and back to a point where the roof is thickest. Centering is then placed adjacent 30 to the opening to be filled and the repairing material as, for example, refractory bricks, are filled into the opening upon the centering, it being understood that such repairs 35 are made as soon as possible after the furnace has ceased to be fired, my improved device being used in connection with the supporting of the centering.

My primary object is to provide a novel, simple and inexpensive construction of 40 hanger unit for use in the repairing of furnace roofs, and more particularly, though not exclusively, in the repairing of roofs in accordance with my improved method hereinbefore referred to.

45 Referring to the accompanying drawings:

Figure 1 is a cross-sectional view of a furnace structure illustrating it in the process of being repaired in accordance with 50 the method hereinbefore referred to and employing my improved hanger units for supporting the centering, this view being taken at the line 1—1 on Fig. 2 and viewed in the direction of the arrows; and Fig. 2, an enlarged section taken at the line 2—2 on Fig. 55 1 and viewed in the direction of the arrows.

Referring to the drawings, a furnace, the roof of which is to be repaired, is represented at 3, the roof being indicated at 4 and shown of arched form transversely of 60 the furnace structure. The dotted line 5 represents, by way of example, the inside of the roof where it is partly burned out and is to be repaired, the roof at this point in accordance with common practice, being removed to provide the rectangular shaped 65 opening 6 forming the void to be filled for effecting the repair. This being done, the operator positions in opening 6, and preferably in spaced relation, hanger units 7 which 70 are supported from the roof 4 at opposite sides of the opening 6, as by resting upon the upper surface of the roof and present a support for a plate 8 or plates, by preference of metal which form a centering and extends 75 to a point adjacent the underside of the roof 4. The centering thus provided forms a support upon which the bricks, or other material, for filling the opening 6 are placed. The hanger units 7 are each formed of a pair 80 of side bars 9 provided at their upper ends with outwardly extending flanges 10, and with a cross-member 11 at its lower end, the parts of the hanger unit being formed integrally, as shown in the drawing, these 85 units being preferably constructed of metal.

In the use of the hanger units for repairing a roof, the units are introduced into the opening 6 from the top of the roof 4 to a position in which these units rest at their 90 flanges 10, upon the portions of the roof surrounding the opening 6, as illustrated. The workman then lays across the cross-members 11, to form the centering hereinbefore referred to, the plate 8, or plates, and the repairing material then filled into the opening 6, as hereinbefore stated. In the use of this form of device the hanger units 95 would remain in the roof until burned away.

100 It will be understood that in using hanger units as described, the workmen in repairing the roof are stationed at all times exteriorly of the furnace chamber and the centering serves as a shield to protect the 105 workmen against the heat of the furnace; furthermore the repair of the furnace may be effected more expeditiously and while the furnace is relatively hot, especially because of the fact that the hanger units may be 110 quickly applied to operative position in the opening to be filled with the repair mate-

rial, thereby saving the time of the workmen and minimizing the time during which the furnace is idle, with consequent saving in expense of labor and operation. The 5 centering, when of metal, also serves the useful function of permitting the fresh material filled into the opening 6 to be gradually heated, when the furnace is refired, with the result of preventing spawling of 10 the material and by the time the centering has dropped away from the position shown in the drawings, the repair material has become heated to such a degree that spawling will not thereafter take place. 15 Another desired result which may be accomplished by using my hanger units, in the manner shown in the drawings; namely by supporting the units at the flanges 10, upon the upper surface of the roof 4, is that 20 these units are caused to take positions substantially conforming to the curvature of the upper surface of the arched roof, the

centering thereby also becoming arched, as shown in Fig. 1 whereby the repair material, when in brick form, will substantially conform at its upper and lower surfaces with the arc-shaped top and bottom surfaces of the roof and thus produce a neater job. 25

What I claim as new and desire to secure by Letters Patent is: 30

A hanger unit for use in repairing the roofs of furnaces adapted to be positioned in the opening to be repaired, comprising an integral U-shaped member having side bars of a length substantially equal to the 35 thickness of the roof to be repaired and connected with a cross member at their lower ends, the upper ends of said side members being provided with outwardly extending flanges adapted to be supported at the edge 40 portion of the opening in the roof, whereby said hanger forms a support for the repair material.

BENJAMIN GOLD.
